JOHN J. SULLIVAN, OF IPSWICH, MASSACHUSETTS, ASSIGNOR TO HAMEL SHOE MACHINERY COMPANY, OF LYNN, MASSACHUSETTS, A CORPORATION OF MASSACHUSETTS.

HEEL-BREASTING MACHINE.

1,129,136.

Specification of Letters Patent. Patented Feb. 23, 1915.

Application filed May 27, 1914. Serial No. 841,364.

To all whom it may concern:

Be it known that I, JOHN J. SULLIVAN, a citizen of the United States, residing at Ipswich, county of Essex, State of Massachusetts, have invented a certain new and useful Improvement in Heel-Breasting Machines, of which the following is a specification, reference being had therein to the accompanying drawings.

10 In the manufacture of boots and shoes and especially of women's shoes having high heels, it is necessary to finish or trim the breast or front portion of the heel. The contour of the breast of the heel may be a straight line or some regular or irregular curve, as for instance, in so-called "Louis" heels. Heretofore, so far as known to me, the operation of trimming the breast of the heel has been accomplished either by power 15 operated rotary knives to which the shoes are presented by hand, or by hand-trimming, this latter method being necessary where the heels have an irregular curve. Heel-breasting machines having rotary knives are all 20 so dangerous that it has been found very difficult to get workmen who are willing to operate them, and it is necessary to pay 25 much higher wages on account of the danger.

The object of my invention is to produce a machine which will finish satisfactorily the breasts of heels having any of the various curves now commonly found in shoes of this character.

30 In the machine embodying my invention in its preferred form, I employ two reciprocating knives of the contour required by the particular heel to be finished. These reciprocating knives are caused to move inwardly from the sides of the heel and preferably meet in the center. By this construction, the cut is made from the outside of the heel toward the center and therefore a true smooth edge on each side of the heel 35 is formed and no bur or rough edge is left, thereby obviating a second finishing operation. It results that the machine embodying my invention gives to the heel a better finish, especially at the edges than has heretofore been possible.

The machine embodying my invention is very simple in construction, and requires no skill on the part of the operator. It always

produces the correct curve on the heel regardless of the skill of the workman. It is also so constructed that the operator's hands are engaged at the time when the knives are coming together and therefore the danger of injury to the operator is eliminated.

I also construct the machine so that after the shoe is put in place and the machine has been started by the operator the pair of reciprocating knives move inwardly and make the cut, and then move outwardly and come to rest automatically so that the operator does not have to stop the machine. The machine is also so constructed that right and left shoes may be trimmed in the same machine without any adjustment of the machine or operation on the part of the workman except that of inserting the shoe. Means are provided so that the shoe is held securely in place and the correct cut is always made.

I believe my machine to be the first of its kind and that the invention is a broad one and therefore do not limit myself to the particular form shown in the drawings although I believe this form to be the most useful embodiment of my invention.

The invention will be fully understood by reference to the following description taken in connection with the accompanying drawings and the novel features thereof are pointed out and clearly defined in the claims at the close of this specification.

In the drawings, — Fig. 1 is a front elevation partly broken away of a machine embodying my invention. Fig. 2 is a section on line 2—2 Fig. 1 looking in the direction of the arrows and showing the parts in the position they occupy when the shoe is inserted and the machine is in operation. Fig. 3 is a section taken on line 3—3 Fig. 1 looking in the direction of the arrows showing the stop mechanism in position to allow the machine to operate. Fig. 4 is a section on line 4—4 Fig. 1. Fig. 5 shows the cutting mechanism of a machine embodying my invention in modified form.

Referring now to the drawings, and particularly to Fig. 1, at A is shown a suitable frame and bed plate for the machine. 11 designates a guideway upon which are supported the jack and toe rest which are of special construction. The jack consists of

a slide 12 resting in said guideway 11 and having formed as a part thereof a hollow post 9 within which is received an upright slide 13. Said post 9 is slotted as shown at 5 14 to permit the vertical movement of a pin 17 secured to the upright slide 13 and resting on the upper side of the end of a lever 15. It will therefore be seen that the slide 13 may be raised or lowered for the length 10 of the slot 14 by a movement of the lever 15. The upper end of the slide 13 is provided with a pin 18 engaging a thimble 19 in the heel of the last 20 on which the shoe is placed. The lever 15 is pivoted at 16 to a 15 post 21 which is supported on a base 22, said base being mounted in guideway 11 and being adjustably secured therein. The lever 15 is operated by a treadle 23 connected to the lever by a suitable connection 24. When 20 the treadle 23 is depressed, the jack and last are raised into position for the heel to be operated upon, as may be seen in Fig. 2.

At 25 is shown a heel rest mounted in a bracket or arm 28 which is adjustably 25 mounted on a rod 281 attached to the frame A of the machine. The heel rest 25 has a slight downward projection 27 at the forward edge of the heel which serves to position the heel properly, and also to form a 30 guide against which the front edge of the top lift of the heel of the shoe is placed.

The heel rest 25 is adjustable vertically in the bracket 28, in the following manner: The post 26 (see Fig. 2) is slidable in a bore 35 29 in the bracket arm 28 and is drilled and tapped at its upper end as shown at 30 to receive a screw threaded adjusting spindle 31 provided at its upper end with a knurled head 32. The spindle 31 is grooved as shown 40 at 33 and this groove is engaged by a pin 34. It will therefore be seen that when the head 32 is turned the heel rest 25 will be raised or lowered slightly simply for purposes of adjustment. The shoe and last are placed on 45 the upper end of the jack when the jack is in its lowest position, and then the operator depresses the treadle and raises the shoe until the heel contacts firmly with the underside of the heel rest.

50 The toe rest comprises a base 35 adjustably mounted on the jack-supporting slide 12 by means of a hand screw 36 and slot 361, said base 35 together with slide 12 being slidable in guide-way 11 for purposes of adjustment for various sizes of shoes. On the base 35 is a post 37 which is drilled to receive the rod 38 on the upper end of which the toe rest is placed. This rod 38 is adjustable vertically and is secured in place by the screw 55 39. On the upper end of the post 38 is a cross-piece 40 provided at its two ends with two vertical horns 41 and 42. The cross piece 40 is covered with a pad comprising a leather covering 43 and a suitable soft filling 60 44. This pad forms a suitable rest for the

shoe so that the fore part of the shoe will not be marred during the operation of trimming the heel. The two horns 41 and 42 are adjustable longitudinally of the cross piece 40 and are held in adjusted position by means of two set screws 45 and 46 to determine the position of the shoe in the machine. When a left shoe is in position to be trimmed, it is held by the operator against the horn 42, while a right shoe is held against the horn 41. It will be seen that by this device, the shoe whether right or left may be properly positioned without any change of adjustment in the machine, or any special effort on the part of the operator, so that the Louis breast is given the proper angle to the axis of the shoe.

At 47 and 48 are shown the two trimming knives. They are in effect chisels or gouges having cutting edges a and are shaped according to the peculiar form of heel which it is desired to produce. It will, therefore, be seen that the correct breast will be given to the heel without any skill on the part of the operator. The said knives are mounted on the ends of reciprocable slides 49 and 50 mounted in guideways formed in the upper ends of the brackets 51, 52, 53, and 54, which extend upwardly from the bed plate A of the machine. At 55 and 56, are shown two collars secured to the respective slides by set screws 57 and 58. These collars are respectively formed with an upwardly projecting member 59 and 60 slotted to receive bars 61 and 62, secured respectively to the upper ends of the posts 51 and 53. These bars are held in place by the set screws 63 and 64 respectively. By this construction, a round slide rod may be employed and the reciprocating knives will be prevented from twisting, springing or getting out of alignment. The said knives are reciprocated by the connecting rods 65 and 66 and by crank plates 67 and 68 mounted on the ends of vertical shafts 69 and 70. At the lower end of each of said shafts, are beveled gears 71 and 72 meshing with corresponding gears 73 and 74 on the main shaft 75. The gears 73 and 74 bear a 2 to 1 relation to the gears 71 and 72 and therefore two rotations of the main shaft 75 are required to produce one complete reciprocation of the cutting knives. During two revolutions of the main shaft 75 of the machine, the cutting knives 47 and 48 move together and meet at the center of the heel and then separate to permit another heel to be put in place, coming to rest in this position as will be hereinafter explained. The length of the stroke of the knives may be varied as required by means of slots 7 and 78 in the crank plates 67 and 68.

At 101, see Figs. 1 and 2, I have shown a rod mounted at one end in the post 53, the other end being supported on a stop 102 on post 51. This rod 101 serves to protect the

hands of the operator during the operation of the machine and is capable of being moved up out of the way whenever it is desirable to get at the knives for purposes of adjustment, etc.

5 The stop mechanism, by means of which the knives are caused to make one complete reciprocation and then come to rest, will now be described.

- 10 Mounted loosely on the main shaft 75 and constantly running is a driving pulley 80 on which runs a belt 81. Adjacent the pulley 80 and cooperating therewith is located a clutch composed of three members, viz., the outer or driving member 79 which is formed integral with the driving pulley 80, the inner or driven member 82, which is fast to the shaft 75, and an intermediate member 107 which operates to engage and disengage the clutch under control of the starting button and stop motion respectively. The driven member 82 is formed with cam surfaces 83 in the well known manner, and there are the usual rolls 84 located between the cam surfaces and the outer clutch member 79. Within the intermediate clutch member 107 is shown a spiral spring 85, one end of which rests against a pin 86 secured to the intermediate member 107, while the other end rests against the pin 87 secured to the inner clutch member 82. It will therefore be seen that the said spring tends to rotate the clutch members in opposite directions and to cause the rolls to ride up the cam surfaces 83 and wedge themselves between the cam surfaces and the outer clutch member. The outer surface of the intermediate clutch members 107 is formed with a shoulder 89. On the bevel gear 72 is placed a projection 94 which as the gear rotates engages a finger 104 on one end of a lever 173 pivoted at 174 to the frame of the machine. The upper end of the said lever 173 is held to the right, as seen in Fig. 1 except when it operates to allow the clutch to engage. At 90, is shown a push button by means of which the operator starts the machine. This push button is on the upper end of a rod 91 (see Figs. 1 and 3) slidably mounted in a lug 103 on the bed plate A of the machine, and is connected at its lower end as shown at 92 to a vertical rod 93 slidably mounted in a lug 95 extending from the bed plate A of the machine. A spring 96 tends to hold the push button and rod 93 in their highest position. The upper end of the rod 93 is in the path of the shoulder 89 and in position to be engaged thereby and thus at times to prevent the rotation of the intermediate clutch member 107, thus disengaging the clutch. At 97, is shown a catch supported on a rod 98, one end of which is pivoted at 99 to the lower end of the lever 173. It will therefore be seen that when the operator

pushes down the push button 90, the upper end of the rod 93 is moved out of engagement with the shoulder 89 and the clutch spring 85 then acts, causing the clutch rolls 84 to lock the two clutch members 79 and 82 together. Thereafter the main shaft 75 will be caused to rotate by its connection through the clutch with the driving pulley 80. When the push button is pushed down a spring 175 pulls the upper end of the lever 173 to the left as shown in Fig. 1 and this moves the catch 97 into the path of the upper end of the rod 93 so that the rod is then held out of the path of the shoulder 89 on the outer surface of the intermediate clutch member 107, as shown in Fig. 3. The rotation of the machine is thus started, and the main shaft 75 makes two revolutions. Near the end of the second revolution of the main shaft, the projection 94 on the gear 72 engages the finger 104 on the upper end of the lever 173 and pulls the stop 97 out of the path of the rod 93 so that the spring 96 can then pull the rod 93 and connected parts up into the path of the shoulder 89 on the intermediate clutch member 107. This occurs just before the shoulder 89 comes around so that the shoulder engages the rod 93. This stops the further rotation of the intermediate clutch member 107, thereby disengaging the two clutch members 79 and 82 and stopping the machine.

It will be seen from the foregoing that when the operator pushes down the starting button, he starts the machine and the knives move in and trim the heel and then move out and stop in a position separated from each other and ready for the insertion of the next shoe. This construction makes it possible for the operator to place the shoe in the machine, raise the shoe into place by the treadle and then push the push button with his right hand while his left hand holds the shoe in proper position. It will therefore be seen that both hands are occupied at a distance from the knives and the danger of getting them injured is eliminated. It will also be seen that the machine has only one treadle and it is therefore easy and simple to operate and may be operated by unskilled labor.

In Fig. 5, I have shown a modified form of machine in which the operation of trimming the breast of a heel is accomplished by a single correspondingly shaped reciprocating knife or gouge, as shown at 105. In this form of machine I employ a cutting block of wood or other suitable material as shown at 106, so that the knife will cut clearly and not leave a ragged edge. For this purpose, the cutting block is given a contour corresponding with the shape of the heel so it will furnish a support for heel for the entire length of the edge of

the knife. It is also made rotatable so that successive cuts will not come in the same place.

What I claim is:

- 5 1. A heel breasting machine comprising a pair of knives of suitable contour, said knives being movable inwardly from the sides of the heel and meeting in the center of the breast.
- 10 2. In a machine of the character described, the combination of a pair of reciprocating knives of suitable contour, said knives being movable from the sides of the heel and meeting in the center of the breast.
- 15 3. In a machine of the character described, the combination of a pair of reciprocating chisel acting knives of suitable contour, and means for moving said knives from the side of the heel to the center of the breast.
- 20 4. A heel breasting machine comprising a knife shaped to give the proper contour to the heel, means for reciprocating the knife transversely of the shoe and from the edge of the heel inwardly, a support for the last for the shoe, a heel rest, and means for holding the shoe on the last, forcibly against the heel rest.
- 25 5. In a machine of the character described, the combination of a pair of reciprocating knives of suitable contour, means for reciprocating the said knives in unison inwardly from the sides of the heel to meet at the center of the breast, and means for causing the said knives to come to rest at the point most widely separated from each other after each complete reciprocation.
- 30 6. In a machine of the character described, the combination of a pair of reciprocating knives of suitable contour, means for moving said knives in unison in-
- 35
- 40

wardly from the sides of the heel to meet at the center of the breast of the heel, driving mechanism, and a stop motion acting on the driving mechanism to stop the machine after each complete reciprocation.

7. In a machine of the character described, the combination of a pair of reciprocating knives of suitable contour, means for moving said knives in unison inwardly from the sides of the heel to meet at the center of the breast of the heel, a vertically movable jack, and a rigid heel rest against which the heel of the shoe rests when the shoe is in position to be operated upon.

8. In a machine of the character described, the combination of a pair of reciprocating knives of suitable contour, means for moving said knives in unison inwardly from the sides of the heel to meet at the center of the breast of the heel, a vertically movable jack, and a rigid heel rest adjustable vertically against which the heel of the shoe rests when the shoe is in position to be operated upon.

9. In a machine of the character described, the combination of a pair of reciprocating knives of suitable contour, means for moving said knives in unison inwardly from the sides of the heel to meet at the center of the breast of the heel, a shoe support, means for moving said shoe support into position for the shoe to be operated upon, and a heel rest by which the vertical position of the heel is determined.

In testimony whereof I affix my signature, in presence of two witnesses.

JOHN J. SULLIVAN.
